UNITED STATES PATENT OFFICE.

GORY O'BRYAN, OF LOUISVILLE, KENTUCKY.

GOVERNOR FOR AIR-COMPRESSORS.

965,120.

Specification of Letters Patent.

Patented July 19, 1910.

Application filed August 9, 1909. Serial No. 512,102.

To all whom it may concern:

Be it known that I, GORY O'BRYAN, a citizen of the United States, residing at Louisville, in the county of Jefferson and 5 State of Kentucky, have invented new and useful Improvements in Governors for Air-Compressors, of which the following is a specification.

This invention relates to a governor or controller for electrically driven air compressors, the object of the invention being to provide a simple and comparatively inexpensive construction of governor embodying a movable switch member controlling 10 the supply of current to the pump motor and controlled in action by a balancing device influenced in its movement in one direction by the air pressure and in its reverse direction by springs or other suitable means, 15 whereby an efficient type of mechanical controller is produced which is positive in action and dispenses with the use of electromagnets and devices embodying a column of oil.

20 The invention consists of the features of construction, combination and arrangement of parts hereinafter fully described and claimed, reference being had to the accompanying drawings, in which:—

25 Figure 1 is a front elevation, partially in section, of a governor embodying my invention, showing the switch in position to close the motor circuit. Fig. 2 is a central longitudinal section of the same. Fig. 3 is a 30 perspective view of the movable switch contact member.

In carrying my invention into practice, I provide an inclosing box or casing 1, made of wood or other suitable material. Within 35 one end of said box or casing is arranged a block 2 having a bore or passage 3 and an internally threaded tubular projection 4 which extends through the adjacent end wall of the casing and receives the proximate end of an air pipe 5 communicating with some suitable portion of the system supplied by the air pump.

A stop plate 6 is arranged upon the face of the block 2 and provided with elongated

slots 7 for the passage of screws 8 entering 50 the block whereby said plate is adjustably secured thereto for a purpose hereinafter described.

The bore 3 forms a cylinder in which is movably mounted a piston 9, which is movable through a stuffing box 10, closing the upper end of said cylinder and serving to prevent escape of air at such point. The piston 9 carries a balancing member in the form of a yoke or forked bracket embodying a cross bar or head 11 and parallel arms 12 extending at right angles therefrom toward the opposite end of the casing.

The arms 12 are provided with reduced cylindrical stems or extensions 13 forming 65 at their points of juncture therewith shoulders 14. Mounted in the opposite end wall of the box from the block 2 are threaded adjusting screws 15 having hollow body portions to receive the free ends of the stems 13 70 and provided at their outer ends with angular heads 16 for the reception of a wrench, whereby they may be adjusted. The piston 9 is movable upwardly, or in the direction away from the block 2 and toward the 75 screws 15, by the air pressure within the cylinder 3, and springs 17 are provided to balance the yoke and bracket against such pressure. These springs encircle the stems 13 between the shoulders 14 and screws 15 80 and exert a downward pressure against the yoke in opposition to the air pressure. By adjusting the screws 15 in or out, the tension and resistance of the springs to the air pressure may be increased or diminished as circumstances may require to secure the desired sensitiveness of operation.

Arranged within the upper end of the casing at a point between the stems and adjusting screws is a supporting block 18 of 90 wood or other suitable material, which block is provided with an elongated slot 19 for the passage of a screw 20, whereby it is adjustably secured in position. The block is provided upon its sides with strips 21 of fiber 95 or other suitable non-conducting material, to which are secured contacts 22 and 23 having terminal relatively converging con-

2 tact portions 24. The sections 25 and 26 of an electric feed wire leading to the pump motor are connected with the respective contacts, thus disposing the governor in the motor circuit.

5 A movable switch or contact member 27 is provided for coöperation with the contacts to open and close and thus control the circuit and the supply of current to the pump 10 motor to regulate the action of the latter, to maintain a determined pressure in the system. This switch member comprises a body portion of fiber or other suitable material provided at each end with a transverse contact head 28, each formed with beveled ends 15 to enter between and engage the surfaces of the contact terminals 24. The said switch member 27 is detachably secured by screws 29 or otherwise to a bar, plate or shank 30, 20 which extends outwardly through the space between the arms of the yoke and is pivotally mounted at its rear end upon the bottom or rear wall of the casing, as indicated at 31. The movable switch member is thus 25 mounted for movement in an arc to bring the contact head 28 nearest the block 18 into or to throw it out of engagement with the contacts, as will be readily understood. The body portion of the switch member is centrally secured to the shank 30, so that when 30 the head 28 arranged to coöperate with the contacts is unduly worn, burned or otherwise rendered unfit for use, the switch member may be reversed upon the shank to bring 35 the other contact head in position for use. As the movable switch member in its movements, plays between the contacts carried by the block 2, provision is made, by the adjustable mounting of said block 18 and plate 6, 40 to vary their relative positions to regulate the throw of the movable switch member as occasion requires.

45 The shank 30 is provided at its sides with bearing sockets 32 to receive partially circular heads 33 upon the inner ends of a pair of oppositely disposed switch operating rods 34, thus forming a ball and socket or universal connection between the switch and rods. The outer ends of said operating 50 rods, which extend at right angles to the plane of movement of the switch, project into outwardly flaring or conical openings 35 formed in the arms 12, whereby said rods are slidably and pivotally connected with 55 the yoke, so that reverse movements may be imparted thereto to actuate the switch on the movements of the yoke. A coiled spring 36 surrounds each rod between the socket 32 and a washer 37 bearing against the adjacent arm 12, such springs operating to 60 impart movement to the rods to actuate the switch member, as well as to cushion the movements of the latter.

65 It will be understood from the foregoing description that the balancing member or

yoke controlling the switch member is subjected on one side through the air pressure in the system and on its reverse side to the counteracting pressure of the springs 17, whereby the yoke will be maintained in 70 switch member closing position when the pressure in the system is at or near the normal pressure desired, so that a current will be constantly supplied to the pump motor as long as such condition exists. In this position, as shown in Figs. 1 and 2, the upper head 28 of the switch member 27 engages the contact terminals 24, and the switch member lies at the limit of its upward movement, in which position the rods 34 are substantially horizontal and arranged in alignment, so that the pressure of the springs 36 maintains the switch member in closed position. When, however, the pressure in the system falls below the desired normal pressure, 80 the spring 17 forces the yoke downward against the counteracting air pressure, whereby the outer ends of the rods move downwardly therewith, thus disposing said rods at an upward and outward angle, so 85 that their springs 36 will exert pressure on the shank 30 and throw the switch member 27 upwardly and into engagement with the contacts 24 or maintain it in such engagement, if already closed, to establish or maintain a supply of current to the motor. Hence 90 the pump will continue to work until the normal air pressure is restored.

If, in operation, the air pressure in the system should exceed the normal pressure, the 100 preponderating pressure of the air in the cylinder 3 will force the yoke upward against the resistance of the spring 17, thus moving the rods 34 to the opposite angular position, whereupon the springs 36 will exert their 105 expansive energy to force the shank 30 downward and thus throw the switch out of engagement with the contacts, breaking the circuit until the air pressure again falls to the normal, when the switch will be thrown 110 to closed position in the manner previously described. Where the pressure fluctuates at times above and below normal, the switch will play back and forth, being thrown into and out of engagement with the contacts, to 115 make or break the circuit as occasion requires to maintain the air pressure at the normal.

120 It will be apparent that the flaring form of the openings 35 in the arms 12, whereby the rods 34 are slidably and pivotally connected with said arms, permits the rods to assume the different angular positions described in a ready and easy manner, and that the operation of the governor to control the 125 degree of air pressure may be regulated at any time by adjusting the screws 15 to control the resisting action of the springs 17.

130 Stops 38 are provided upon the casing to limit the downward movement of the yoke

or balancing member, the upward movement of which is restricted by the springs 17. The downward movement of the switch is limited by engagement of the lower head thereof with the stop plate 6, which may be adjusted as occasion requires for this purpose to limit the strain upon the springs 36 and prevent displacement of the rods 34 from the openings 35 through an excess downward movement 10 of the yoke. As the acting switch head is liable under some conditions to arc and stick or hang between the contact terminals 24, a releasing device 39 is provided to break connection and assist the springs 36 in this action. This releasing device comprises one or more members extending between the stems 13 and pivotally mounted upon brackets 40 carried by the strips 21 or the block 18. The forward end of said device 20 has a finger or bent portion 41 normally arranged between the contacts, blocks 18 and acting head of the switch, to engage and force said switch to a circuit opening position. The rear end of the releasing device 25 is arranged in the path of movement of a contact rod 42 extending between the arms of the yoke, so that when the yoke moves upwardly, the releasing device will be swung to force the switch member 27 out of engagement with the contacts in a positive manner. The rod 42 is preferably provided with a set screw or adjustable contact member 43 to engage the releasing device, whereby the point of contact may be varied as required to compensate for the adjustment of block 18.

From the foregoing description, taken in connection with the drawings, the construction and mode of operation of my improved 40 governor will be readily understood, and it will be seen that the invention provides a governor which is simple of construction, positive in action, adapted to be regulated for its sensitiveness and control the degree of normal air pressure, and which dispenses with the use of electro-magnets or balancing means employing oil columns and other like devices which are liable to easily get out of order.

50 I claim:—

1. A governor for electrically operated air pumps comprising a cylinder, a piston operating therein, a yoke carried by the piston and movable in one direction under air pressure, springs connected with the arms of the yoke for counteracting the air pressure, circuit terminals, a pivotally mounted switch member movable into and out of engagement with said terminals, rods 55 pivotally connected with the movable switch member and slidably and pivotally connected with the yoke arms, springs associated with said rods for actuating the movable switch member upon the movements of the yoke, and a device connected with and actu-

ated by the yoke for releasing said switch member from engagement with said terminals.

2. A governor for electrically operated air pumps comprising a cylinder, a piston operating therein, a yoke carried by the piston and movable in one direction under air pressure, springs connected with the arms of the yoke for counteracting the air pressure, circuit terminals, a pivotally mounted switch member movable into and out of engagement with said terminals, rods pivotally connected with the movable switch member and slidably and pivotally connected with the yoke arms, springs associated with said rods for actuating the movable switch member upon the movements of the yoke, and a pivotally mounted releasing device connected with and actuated by said yoke for positively forcing said switch member out of engagement with said circuit terminal. 70 75 80 85

3. A governor for electrically operated air pumps comprising a cylinder, a piston operating therein, a yoke carried by the piston and movable in one direction by air pressure, counteracting springs engaging the arms of the yoke for moving the same in the reverse direction, circuit terminals, a pivotally mounted switch member movable into and out of engagement with said terminals, and operating connections pivotally engaging the arms of the yoke and movable switch member and provided with springs operative to open and close the switch when said connections are moved to different angular positions by the movements of the yoke. 90 95 100

4. A governor for electrically operated air pumps comprising a cylinder, a piston operating therein, a yoke carried by the piston and movable in one direction under air pressure, springs connected with the arms of the yoke for counteracting the air pressure, circuit terminals, a pivotally mounted switch member movable into and out of engagement with said terminals, rods pivotally connected with the movable switch member and slidably and pivotally connected with the yoke arms, and springs associated with said rods for actuating the movable switch member upon the movements of the yoke. 105 110 115

5. A governor for electrically operated air pumps comprising a cylinder, a piston operating therein, a yoke carried by the piston and movable in one direction by air pressure, springs acting upon the arms of the yoke in opposition to the air pressure, means for regulating the pressure of said springs, circuit terminals, a pivotally mounted switch member movable into and out of engagement with said terminals, rods pivotally connected with the switch member and slidably and pivotally connected with the yoke arms, and springs associated with said rods for throwing said movable switch mem- 120 125 130

ber into and out of engagement with said circuit terminals upon the movements of the yoke.

6. A governor for electrically operated pumps comprising a cylinder, a piston movable therein, a yoke carried by the piston, springs acting upon the arms of the yoke in opposition to the fluid pressure upon the piston, means for tensioning said springs, 10 circuit terminals disposed between said

arms, a pivotally mounted switch member to engage said terminals, and operating connections between said switch member and the arms of the yoke.

In testimony whereof I affix my signature 15 in presence of two witnesses.
